(57) **CLAIM**

The ornamental design for a sleeve label with window for packaged comestibles, as shown and described.

DESCRIPTION

FIG. 1 is a perspective view of the sleeve label with window for packaged comestibles with an opaque top band, an opaque middle section and a vertical transparent window with graduation in hours;

FIG. 2 is an enlarged view taken from FIG. 1 for ease of illustration;

FIG. 3 is a perspective view of the sleeve label with window for packaged comestibles in use; and,

FIG. 4 is another view of the sleeve label with window for packaged comestibles in use on a test tube.

The dashed lines in FIGS. 3 and 4 representing a bottle and a test tube respectively, are exemplary of typical use as part of an environmental setting, and form no part of the claimed design.
